UNITED STATES PATENT OFFICE.

BENJAMIN E. D. STAFFORD AND ETHAN I. DODDS, OF PITTSBURGH, PENNSYLVANIA,
ASSIGNORS TO FLANNERY BOLT COMPANY, OF PITTSBURGH, PENNSYLVANIA.

STAY-BOLT STRUCTURE.

1,252,310.

Specification of Letters Patent.

Patented Jan. 1, 1918.

Application filed November 21, 1916. Serial No. 132,596.

To all whom it may concern:

Be it known that we, BENJAMIN E. D. STAFFORD and ETHAN I. DODDS, citizens of the United States, and residents of Pittsburgh, in the county of Allegheny and State of Pennsylvania, have invented certain new and useful Improvements in Stay-Bolt Structures; and we do hereby declare the following to be a full, clear, and exact description of the invention, such as will enable others skilled in the art to which it appertains to make and use the same.

This invention relates to stay bolt structures, and more particularly to means to facilitate the testing of the bolt,—the object of the invention being to provide, in a stay bolt structure, simple mechanical means which may be manually operated without removing any part of the structure, to determine whether the bolt is defective.

With this object in view, the invention consists in certain novel features of construction and combinations of parts as herein-after set forth and pointed out in the claims.

In the accompanying drawings, Figure 1 is a sectional view showing a stay bolt structure embodying our improvements; Fig. 2 is a plan view of the same; Fig. 3 is a plan view of the cap; Fig. 4 is a side view of the rotary driving or testing member; Fig. 5 is a top plan view of said driving or testing member; Fig. 6 is a bottom or inner plan view of said driving or testing member; Fig. 7 is an end view of the bolt head; Fig. 8 is a sectional view showing another form of the invention; Fig. 9 is a plan view of the structure shown in Fig. 8, and Figs. 10, 11, and 12 are views of details of the structure shown in Fig. 8.

1 represents a bearing sleeve threaded externally at 2 to screw into an outer boiler sheet,—the outer portion of said sleeve being somewhat enlarged and threaded as at 3 for a purpose hereinafter explained. The sleeve 1 is made interiorly with a curved bearing for the partly spherical head 4 of a stay-bolt 5, and the inner portion 6 of the bore of the sleeve is made flaring to permit lateral play of the bolt. The bolt head is provided with an angular enlargement 7 for a purpose hereinafter explained.

The threaded portion 3 of the sleeve 1 receives the interiorly threaded portion of a cap 8. Between a shoulder 9 within said cap

and the outer end of the sleeve 1, the annular flange 10 of a rotary driving or testing member 11 is disposed, suitable packing 12 being preferably disposed between said flange and sleeve. The rotary testing member is recessed or made hollow and its bottom wall 13 which enters the outer end of the sleeve 1, is made with an angular opening 14 which receives the angular enlargement 7 on the bolt head,—said opening 14 being of such proportions relatively to the proportions of the enlargement 7 as not to interfere with the normal lateral play of the bolt.

The rotary testing member 11 is provided with an outwardly projecting angular enlargement 15 to receive a wrench. The enlargement 15 of the rotary testing member is inclosed and protected within the outer portion of the cap 8, and this portion of the cap may be made angular exteriorly to receive a wrench.

The cap 8 may be so adjusted normally, as to retain the rotary testing member tightly clamped in place, but when the bolt is to be tested, the attendant may lessen the cap 8, and then apply a wrench to the angular enlargement 15 on the testing member and attempt to turn the latter. If the member 11 refuses to turn more than may be necessary to take up the play between the walls of the opening 14 and the angular enlargement 7 on the bolt head, the attendant will know that the bolt is in good condition. If however, the testing member responds freely (or comparatively so) to the turning force applied by the wrench, the attendant will thus be made aware of the fact that the bolt is broken.

In the embodiment of the invention shown in Figs. 8 to 11, the bearing sleeve 1 is threaded interiorly, as at 16 to receive the external threads of a cap 17 inclosed within said bearing sleeve. This internal cap may rest against a shoulder 18 formed within the bearing sleeve, and said cap is formed with an opening having a beveled wall 19 forming a seat for the beveled peripheral portion of a rotary testing member 20. This testing member is made with an angular socket 21 which receives the angular enlargement 7 on the bolt head 4.

The outer part of the rotary testing member is made angular as shown at 23 to receive a wrench. A collar 24 is threaded on

the shank 22 and bears on an annular bead 25 surrounding the seat 19. This collar may be made with slots 26 to receive a wrench and the cap 17 may also be made with 5 wrench slots 27.

We do not claim broadly, in this case, a testing member to engage the bolt and mounted to be turned to test the integrity of the bolt, the same being covered in our 10 copending application Serial No. 88,146, nor do we claim broadly in this case, the testing member having a part disposed within the cap and operatively associated with the bolt, and a part projecting through the cap, the 15 same being covered in our copending application Serial No. 130,047.

Other changes might be made in the details of construction of our invention without departing from the spirit thereof or 20 limiting its scope and hence we do not wish to restrict ourselves to the precise details herein set forth, except as required by the scope of the appended claims.

Having fully described our invention 25 what we claim as new and desire to secure by Letters-Patent, is:—

1. In a stay bolt structure, the combination with a bolt having an angular portion at one end, and a bearing sleeve, of a rotatable testing member supported by the bearing sleeve and having an angular socket to receive the angular end portion of the bolt.

2. In a stay bolt structure, the combination with a sleeve and a bolt having a bearing therein, said bolt provided with a projecting angular end portion, of a rotatable testing member supported by the sleeve and having an angular socket to receive the angular portion of the bolt, said socket having 40 slightly greater dimensions than the dimen-

sions of said angular projecting portion of the bolt.

3. In a stay bolt structure, the combination with a bearing sleeve, a bolt having a bearing in said sleeve and provided with an angular enlargement and a cap removably attached to said sleeve, of a rotatable testing member mounted within the cap and having an angular socket to receive the angular enlargement on the bolt. 45

4. In a stay bolt structure, the combination with a bearing sleeve, a bolt mounted therein and having an angular enlargement and a cap removably attached to said sleeve, of a rotatable testing member within said 55 cap and having an angular socket to receive the angular enlargement on the bolt, said testing member having an angular portion inclosed within a part of the stay bolt structure. 50

5. In a stay bolt structure, the combination with a bearing sleeve, a bolt having a bearing in said sleeve and provided with an angular enlargement, and a cap removably attached to said sleeve, of a rotatable testing 65 member having an angular socket to receive the angular enlargement on the bolt, and also having a peripheral flange disposed between the cap and the sleeve, said testing member also having an angular projection 70 inclosed within said cap.

In testimony whereof, we have signed this specification in the presence of two subscribing witnesses.

BENJAMIN E. D. STAFFORD.
ETHAN I. DODDS.
